TOOTHBRUSH HOLDER

Vaselei V. Ushanoff, Los Angeles, Calif.

Application June 25, 1951, Serial No. 233,479

2 Claims. (Cl. 312—206)

1

My invention relates to new and useful improvements in hangers or holders for tooth brushes and the principal object of my invention is, to provide a simple, inexpensive and efficient device which will function to maintain the contained tooth brush in sanitary condition.

A further object of the invention is, to provide a tooth brush holder having a body, perforated to receive the handle of the tooth brush and also provided with a depending leg whereby said body may be detachably suspended from the tooth brush suspension fixture or hanger of china, usually found in bath rooms, and, further to provide said body with an upstanding pin or post which provides means for holding the tooth brush cap or cover in position over the bristle end of the brush and also for holding said cap when same is removed, to permit the removal of the brush from said body.

With the foregoing and other objects in view, my invention consists in certain novel features of construction and arrangement of parts hereinafter more fully described and claimed and illustrated in the accompanying drawing, in which:

Fig. 1 is a vertical section taken through the center of a tooth brush holder of my improved construction.

Fig. 2 is a vertical section taken on the line 2—2 of Fig. 1.

Fig. 3 is a horizontal section taken on the line 3—3 of Fig. 1.

Fig. 4 is a detail vertical section showing a modified form of the joint between the lower tooth brush handle cover tube, and the body of the device,

Fig. 5 is a detail vertical section showing a modified form of the joint between the cover and the body 10.

Fig. 6 is an elevational view of an arrangement embodying my invention, for suspending a plurality of the tooth brush holders.

Referring by numerals to the accompanying drawing which illustrates a preferred embodiment of my invention, 10 designates a block molded from plastics or the like material, which forms the body of the holder, said block being formed with a marginal upstanding flange 11 and at the rear, a pin or post 12 projects upwardly to provide a point of attachment for the cover 13 which rests on the body 10, inside the flange 11 while in bristle head covering position.

When cover 13 is removed from body 10 to permit removal of the tooth brush, said cover may be positioned on the pin or post 12, as shown by

dotted lines Fig. 1, thus minimizing the possibility of displacement or loss of said cap, while the brush is being used.

Cap or cover 13 is an open inverted cup shaped member of plastics, metal or the like, adapted to fit on the body 10, within flange 12 and formed integral with cover on its rear face are vertically disposed parallel flanges 14, thus providing a channel 15, which receives post 12 when said cover is positioned on the body 10. Cover 13 may be perforated as designated by 16, to provide air circulation openings.

Depending from the rear side of body 10 preferably in alignment with pin or post 12, is a leg 17, which is passed downwardly through an opening in the standard fixture 18 generally found in bath rooms for the suspension of tooth brushes. Body 10 is provided in its forward portion with an aperture 19 of sufficient size to receive the handle of an ordinary tooth brush B and formed integral with or fixed to said body 10 and surrounding said aperture is a depending brush handle covering tube 20, the lower end of which is preferably open.

In Fig. 4, I have shown a modified form of the connection between the brush handle covering tube 20 and the body 10, such connection comprising an internal rib 21 on the tube which slips over an external rib 22 formed on an integral flange which depends from the bottom of body 10 around the opening 19 therein.

To permit this form of connection to be used, tube 20 is split lengthwise for a short distance through and beyond rib 21.

In Fig. 5, the body 10 is provided on its top with an upward extension 23, which enters the lower end of cover 13 when the latter is placed on said body and which structure is the reverse of the structure shown in Figs. 1 and 2.

In Fig. 6, I have illustrated a multiple arrangement of the tooth brush covers and in this arrangement, base or body 10, is elongated to take care of the added brushes and the covers 13 therefore may be marked "His," "Hers," "Jr." etc.

In the use of my improved tooth brush hanger, the brush, when properly positioned in the holder is shown in Figs. 1 and 2, with the cap 13 positioned on body 10, and with the flanges 14 in engagement with post 12. To remove the brush, cap 13 is drawn upward from body 10 and moved rearward and placed on post 12 as shown by dotted lines, Fig. 1, and the brush is now drawn upward from the body 10 and lower tube 20.

After using the brush, it is restored to its position in body 10 and a reversal of the move-

ments of the parts just described will restore the brush to its protected position in the holder.

An important feature of my improved brush holder, is the body 10, with upstanding pin 12 for receiving cap 13 both in "on and off" positions, also the depending finger 18, for with such construction, said holder may be readily applied to the standard fixtures 18 such as are found in practically the bathrooms of all homes and hotels.

Thus, it will be seen that I have provided a tooth brush holder which is of simple, compact structure, affords maximum protection for the enclosed tooth brush and which is very effective in performing the functions for which it is intended.

Minor changes in the size, form and construction of the various parts of my improved tooth brush holder, may be made and substituted for those herein shown and described, without departing from the spirit of the invention, the scope of which is set forth in the appended claims.

I claim as my invention:

1. The combination, with a standard bath room fixture having a vertical aperture, of a toothbrush holder comprising a block, a leg formed integral with the rear portion of said block and removably positioned in the aperture in said bath room fixture, the block being provided in its top with a shallow depression, a pin projecting upward from said block to the rear of said depression, there being an aperture formed in the depressed portion of said block for reception of a toothbrush, a cap removably seated in said depression for covering the upper portion of a toothbrush occupying said aperture, ver-

tical flanges on the rear portion of said cap for engaging said pin to hold said cap in place, and with an open ended tube depending from the block to provide a cover for the depending portion of said toothbrush.

2. The combination with a bathroom fixture for hanging tooth brushes, said fixture being provided in its front portion with a vertical aperture, of a block having an aperture formed in its forward portion and adapted to receive a tooth brush, an arm depending from the rear portion of said block and adapted to enter said aperture in the fixture, with the block disposed so that the aperture therein is positioned in front of said fixture, a cap removably positioned upon said block above the aperture therein, a post projecting from the rear portion of said block, a way formed in the rear portion of said cap for receiving said post when said cap is positioned on said block and a tube open at its lower end and depending from said block around the aperture therein for protection of the tooth brush suspended from said block.
